UNITED STATES PATENT OFFICE

ROBERT L. DAVIS, OF PITTSBURGH, PENNSYLVANIA, ASSIGNOR TO WESTINGHOUSE ELECTRIC & MANUFACTURING COMPANY, A CORPORATION OF PENNSYLVANIA

TRANSMITTING CIRCUIT

Application filed September 13, 1928. Serial No. 305,722.

This invention relates to radio communication and more particularly to a multiplex system whereby several messages may be sent simultaneously over one system.

5 It has been frequently proposed to transmit from the sending station a plurality of carrier frequencies, each modulated in accordance with its own particular message. The messages may then be received either at several different stations or at the same station by means of a plurality of receiving sets, each tuned to its particular carrier frequency.

10 It has also been proposed to modulate the amplitude of a carrier current of constant frequency with several modulations each having its own characteristic frequency. The several modulations, being applied in turn, a plurality of messages may be sent over the one communication channel.

15 It has also been proposed to modulate a carrier frequency by changing not the amplitude but the frequency thereof. By my invention, I propose to apply the latter method of modulation to a single carrier frequency and thereby send a plurality of messages over what is, in effect, a single radio channel.

20 The method of modulation by changing the frequency differs from the change of frequency made in order to tune the sending set to one or another of several receiving stations in two respects. (1) The changes in frequency are much smaller than the changes used to accomplish said tuning, and (2) they 25 are not great enough to cause the modified frequency to fall outside the range to which the receiving set is sensitive.

25 The small changes of frequency used for "frequency-shift modulation" are produced by changing the conditions under which an oscillation generator, of a type which produces a nearly constant frequency operates.

30 The crystal-controlled vacuum tube and the harmonic generator governed by a tuning fork are the best known examples of such generators. They were originally described as having a constant frequency but further study of them has shown that they change their frequencies slightly in response to large 35 changes in certain conditions. This property

has been used for producing "frequency-shift modulation".

It is an object of my invention to employ a plurality of different frequency shift-modulations upon one carrier frequency to transmit a plurality of different messages simultaneously over one radio channel.

45 It is a further object of my invention to distinguish with rapidity and certainty between the slightly differing frequencies produced by frequency-shift modulation of one carrier frequency.

50 It is a further object of my invention to provide a plurality of translating devices in one receiving set and to provide means whereby each of the several nearly equal frequencies resulting from the above-described frequency-shift modulation shall control one of said translating devices.

55 It is a further object of my invention to provide a plurality of signal-translating devices and to so arrange the above-mentioned frequency-responsive translating devices that the operation of one of them will actuate all of said signal-translating devices in one 60 sense and the actuation of any of the others will operate the respective signal-translating device in the opposite sense.

65 It is a further object of my invention to provide means whereby intermittent production of any one of said nearly equal frequencies during a period constituting an element of the signal shall produce the same effect in the final translation of the signal or a continuous production of said frequency during 70 said period.

75 Other objects of the invention and details of the construction will be readily understood from the following description and the accompanying drawings, in which:

80 Figure 1 is a diagram of the circuits and apparatus at the sending station, and

85 Fig. 2 is a similar diagram for the receiving station.

90 In Fig. 1, the vacuum tube 1 has associated with it the usual circuits to constitute an oscillation generator, the frequency of which is fixed by the piezo-electric crystal 2. These circuits include an inductor 3 shunted across the crystal. Across a portion of the induc- 95

tor 3, vacuum tube 4 is connected. The connection includes a B-battery 5, and both tube and battery are connected to the inductor through a condenser 6 and the usual C-battery 7.

6 It has been discovered that, with such arrangement, the frequency of the oscillations generated by the tube 1 will change somewhat in response to changes of the potential upon the grid of the vacuum tube 4. To 10 provide these potential changes, I connect the grid through a resistor 10, and a small portion of the battery 11 to the filament. Additional portions of the battery 11 are connected to the grid through key-controlled 15 devices.

The keys 12, 13, and 14 are connected, respectively, to points of the battery 11, including successively larger portions thereof. The key 12 is connected, through a slip ring 15, to a segment 16 of a commutator wheel 17. Similarly, the key 13 is connected, through a slip ring 18, to a segment 19, and the key 14 is connected, through a slip ring 20 21, to a segment 22. The segments of the wheel 17 are insulated from each other and from the central portion of the wheel. The slip rings and wheel are mounted upon a shaft 23 which is intended to represent any 25 suitable driving means. The shaft is driven at such speed that all of the segments will be engaged by the brush 24 several times during the shortest time that the key remains either open or closed in normal operation of 30 the device. The brush 24 is connected to the resistor 10 and the grid of the tube 4.

The output circuit of the oscillation generator 1 supplies energy to the amplifier which delivers energy to the antenna 27. 40 Instead of an antenna, the device may, if preferred, deliver its energy to a line for carrier-current communication. Instead of a simple amplifier, the device may, if desired, include a frequency multiplier.

45 In the receiving system illustrated in Fig. 2, an antenna 31 is shown, which, if preferred, may be replaced by any of the usual devices for receiving high frequency energy from a carrier-current line. The connections from the antenna 31 to the detector 32 include the secondary 33 of a transformer through which a frequency differing slightly from the carrier frequency is introduced. This heterodyne frequency is provided from 50 any suitable source, such as the oscillation generator 34. The connections from the antenna 31 to the detector 32 may include any of the usual or known features of a heterodyne receiver which it is desired to employ.

55 The output of the detector 32 is delivered to a plurality of frequency-selective devices such as filters, tuned circuits or the like arranged in parallel. The first of these (35) is series resonant to the beat frequency which arises between the energy received

from the antenna 27 and the energy from the generator 34 when all of the keys 12, 13 and 14 are open. The next (36) is series resonant to the beat frequency between the energy from the generator 34 and that from the 70 antenna when the key 12 is closed and the brush 24 is on the segment 16. The next (37) is series resonant to the beat frequency which corresponds to conditions when the key 13 is closed and the brush 24 is on the segment 19. 75 The next (38) is series resonant to the beat frequency when the key 14 is closed and the brush 24 is on the segment 22.

80 From the point of greatest potential change in a series-resonant circuit, a connection is made, over a condenser, to the grid of a vacuum tube. Thus, from the junction between the inductor and the condenser in the first tuned circuit 35, over the condenser 41, a connection is made to the grid of a vacuum tube 42. The grid of this tube is connected to the filament over a grid leak 43, and the plate circuit of the tube 42 includes the winding of a relay 44 and a B-battery 45.

85 The tuned circuit 36 is similarly associated with a vacuum tube 46, the plate circuit of which includes the winding of a slow-acting relay 47 and the B-battery 45. The tuned circuit 37 is associated in the same way with a vacuum tube 48 controlling a slow-acting relay 49, and the tuned circuit 38 is associated with a vacuum tube 51 controlling a slow-acting relay 52.

90 The contacts of the relay 44 are connected in series with the left-hand windings of three 100 differential relays 54, 55 and 56 and to battery 57. This series arrangement may, if desired, also include a rheostat 58 for adjusting the forces exerted by said left-hand windings.

95 The contacts of relays 47, 49 and 52 are connected in parallel, the parallel circuits being energized from a common battery 61 and including, respectively, the right-hand windings of the relays 54, 55 and 56. Each of 110 these relays actuates any desirable signalling device. For the purpose of illustration, these are shown as recorders, whereby the messages are marked upon moving tapes.

115 In the operation of the device, the oscillation generator 1 produces a frequency which is nearly constant. Small changes in this frequency occur as described below, but the changes are a very small percentage of the normal frequency which has been referred to herein as the carrier frequency. The carrier frequency is amplified in the amplifier and delivered to a line or to space over the antenna 27.

120 When all the keys 12, 13 and 14 are open, the frequency thus delivered is the carrier frequency, regardless of the position of the commutator wheel 17. This may, instead of being the frequency generated by the tube 1, be a multiple thereof, if the amplifier is 125 130

made to deliver some harmonic instead of the fundamental frequency.

The carrier frequency, is received on the antenna 31 and produces, with the energy 5 from the generator 34, a beat note which, amplified, if desired, is delivered by the detector 32. This frequency produces little effect upon the tubes 46, 48 and 51 because the tuned circuits 36, 37 and 38 are not resonant 10 to it. The tuned circuit 35, being resonant to this frequency, impresses a larger potential of this frequency upon the condenser 41 and, thus, upon the grid of the tube 42.

The tube 42, under these circumstances, will 15 deliver a much smaller plate current than when oscillations are not impressed upon the grid thereof. Consequently, the relay 44 releases its armature, and the circuit through all of the left-hand windings of the relays 54, 20 55 and 56 is energized. If, at this moment, the right-hand winding of any of these relays is de-energized, the corresponding indicating device will be moved by the left-hand winding.

25 When key 12 in Fig. 1 is closed, the potential upon the grid of the tube 4, instead of corresponding, all of the time, to the portion of the battery 11 between the filament and the resistor 10, will, at times, correspond to 30 the potential of that portion of the battery between the filament and the connector to the key 12. The latter correspondence occurs each time that the sector 16 comes into contact with the brush 23.

35 Thus, if the shaft 24 is rotating fifty times per second and the shortest time that the key 12 is closed in normal operation is a fifth of a second, there will be at least ten intervals during which the frequency delivered from 40 the antenna 27, instead of being the normal carrier frequency, differs therefrom by an amount corresponding to the potential controlled by the key 12.

The shortest time that the key is closed, 45 or open, is a period constituting the signal element. The signal will be made up of combinations of this period with multiples thereof grouped together to form the code characters.

50 When the key 12 is closed for a longer time, there will be more than ten such intervals during its closure, but, regardless of the number of intervals during which the frequency, characteristic of the key 12, is radiated, the 55 total time which such radiations endure will be one-third of the time the key 12 is closed. During the other two-thirds of the time, the brush 24 is not in contact with the segment 16 and the key 12 is, therefore, without effect 60 upon the radiated frequency.

65 During each of the intervals that the frequency of the radiations corresponds to the potential controlled by the key 12, the radiations received at the antenna 31 will combine 70 with the energy from the generator 34 to

produce, in the output of the detector 32, a beat frequency which is not readily conducted through the tuned circuit 35 but is readily conducted through the tuned circuit 36. This beat frequency is therefore, without effect 75 upon the tube 42 or the tubes 48 and 51 but produces a diminution in plate current from the tube 46 and thus a diminution in the current in the winding of the relay 47.

The slow-acting character of this relay 75 prevents the armature from moving in response to each of these intervals, but the diminution of the plate current during a third of the time is approximately equivalent to a diminution one-third as great enduring 80 throughout all the time that the key 12 is closed. The relay 47 is adjusted to permit the contacts to close in response to this diminution. The right-hand winding relay 54 is, therefore, closed as long, or substantially 85 as long, as the key 12 is closed.

The left-hand winding of the relay 54 is energized by current from the battery 57 during not more than two-thirds of the time that the key 12 is closed. It will be quite two-thirds if, and only if, the keys 13 and 14 remain open all the while that the key 12 is closed. The left-hand winding of the relay 54 is so designed and the rheostat 58 is so adjusted that it is only when the current from the battery 57 is present in the left-hand winding all of the time that it is able to counteract the current in the right-hand winding. Consequently, the armature of the relay 54 moves in the direction corresponding to the 90 right-hand winding so long as the key 12 is closed.

95 Similarly, the relay 55 will be under the influence of its right-hand winding so long as the key 13 is closed, and the relay 56 will be 100 under the influence of its right-hand winding so long as the key 14 is closed.

Closure of the key 13 is without effect upon the relay 54 because it does not influence the movement of the armature of relay 47 and its 105 effect upon the movement of the armature of relay 44 is only to diminish by another third the time (already diminished by one-third) during which there is current in the left-hand winding.

110 It will be apparent from the foregoing that the relay 44 is the only one which must act as rapidly as the segments of the wheel 17 pass the brush 23. The relays 47, 49 and 52 need be no more rapid than the keying frequency, and the relays 54, 55 and 56 need be no more rapid than the keying frequency. If it is desired to operate wheel 17 at a higher speed than that to which the armature movements of a relay of the type shown at 44 can correspond, a relay of the vacuum tube type 120 may be substituted for the relay 44 without difficulty.

125 Because the several messages are conveyed by frequency changes instead of amplitude 130

modulation, it is possible to receive them by a heterodyne instead of an ordinary detector. The greater sensitiveness of the heterodyne method of reception is then combined with multiplex communication.

5 Other changes in details of the construction will occur to those skilled in the art without specific mention thereof. The description of only one specific form of the apparatus is not to be construed as a limitation. No limitation 10 is intended except as indicated in the accompanying claims or required by the prior art.

I claim as my invention:

15 1. In a radio multiplex transmitting system, a crystal-controlled oscillation generator, circuits associated with said generator including a variable impedance for changing the frequency of the oscillations generated thereby, a plurality of separately controlled 20 means for bringing said impedance to respectively predetermined values and cyclic means for operatively relating said impedance to each of said separately controlled means in turn, the speed of said cyclic means being sufficient to operatively relate the impedance to any one of said separately controlled means a 25 plurality of times during the normal period of action, of the separately controlled means.

30 2. In a radio multiplex system, a crystal-controlled oscillation generator, a plurality of keys, means controlled by said keys for causing said oscillation generator to produce frequencies which differ from the frequency generated thereby when all said keys are in 35 inoperative position by amounts respectively predetermined for each key, a commutator connecting each key in turn to said means, said commutator being driven at a speed sufficient to connect each key to said means a 40 plurality of times during one period of normal keying frequency and a transmitter controlled by said generator.

45 In testimony whereof, I have hereunto subscribed my name this 6th day of September 1928.

ROBERT L. DAVIS.
